APPARATUS FOR PACKAGING ARTICLES

James A. Kerr, Pawtucket, R. I., assignor to
Providence Braid Company, Pawtucket, R. I.,
a corporation of Rhode Island

Application April 5, 1926. Serial No. 99,787

67 Claims. (Cl. 28—21)

This invention pertains to apparatus for packaging elongate flexible strand-like articles and that embodiment of the invention chosen for illustration is concerned with the packaging of 5 tipped laces, for example shoe laces. While adapted to package one or more such strand-like objects the invention is herein specifically described with reference to the packaging of such articles in pairs, the operation performed being 10 that commonly known as respects the packaging of shoe laces as "pairing".

Shoe laces, at least those of all but the lowest grades, are commonly sold in pairs, the two laces constituting a pair being arranged in the form 15 of an elongate coil or skein and being bound together by means of a paper or other appropriate cincture.

The trade demands that the packaged laces present a neat and attractive appearance, each 20 package being of substantially uniform length and with the ends of the laces bound in by the wrapper. Moreover in packaging flat laces custom requires that each lace be wound or coiled upon itself without twist to form a skein or 25 coil independent of its companion lace and that the two skeins or coils be disposed in parallel face to face relation in the package. Since the laces as received from the tipping machine are not always of exactly the same length care is re- 30 quired in winding them so that the ends of both laces of a pair shall be bound in by the wrapper and since the braid of which the laces are usually prepared sometimes has a slight tendency to twist it is not an altogether easy problem to wind 35 the two laces simultaneously to form the parallel skeins demanded by the trade.

The usual present day practice in pairing shoe laces consists in simultaneously winding the laces of the pair by hand to form skeins and then, by 40 hand, binding the skeined laces together by means of a paper wrapper. The operator is usually furnished with a small hand reel having parallel arms, one at least of which is furnished with a clip, slot, or other device for receiving 45 one end of each lace. In using the reel the operator inserts the end portions of the two laces side by side in the slot or clip, determining the 50 distance to which the tips extend beyond the retaining means by the use of a suitable gauge. The operator then turns the reel with one hand while holding the depending laces be'ween the 55 thumb and fingers of the other hand, thereby tensioning and keeping them smooth, untwisted and substantially parallel as they are wound to

set that the inner ends of the laces are disposed substantially at the center of the skein while the reel arms are so spaced that the ends of the laces which are at the outside of the skein are located near the center of length of the skein or at least 60 inwardly from the ends thereof.

When the paper wrapper is now applied to the central part of the skein the inner pair of tips is entirely concealed while the outer ends of the laces are bound in at a point so near to the 65 tips that the tips, if not actually covered by the wrapper, are kept within the bounds of the package.

While this mode of hand packaging produces satisfactory results, it is an operation which re- 70 quires a considerable degree of skill and manual dexterity, if it is to be performed at economical speed, and at best constitutes a considerable item in the cost of lace manufacture. The prin- 75 cipal object of the present invention is to pro- 80 vide novel apparatus by means of which the laces may be packaged in a satisfactory manner but more rapidly than by present methods and with a minimum requirement of attention from an operator, the laces being delivered if desired 85 directly from the tipping machine to the packag- 90 ing apparatus.

While I herein employ the term "skein" as a 95 convenient mode of describing the general shape and appearance of the laces after reeling, I use it without reference to the length of the material being reeled and do not intend it to be construed in the narrow and technical sense in which it is employed in the textile arts. In the same way I have used the term "coil" in some instances to 100 designate the reeled article but without any intention of limiting this expression to a coil of circular contour, but while the term "coil" might from some viewpoints be considered as of broader meaning than "skein", I use the latter term herein as substantially synonymous with the former as defining and applicable to a strand-like article so folded, wound, reeled or otherwise manipulated as to form a package comprising a plurality of bights or runs of such article in juxtaposed relation.

Furthermore while the apparatus is particularly useful in pairing shoe laces it is conceivable that it may be of utility in packaging other articles and I have employed the term "strand-like article" as comprehensive of any elongate flexible article of substantially definite length which it may be desired to reel and wrap, either singly or in multiples, to form packages of definite proportions and uniform appearance and 110

of which shoe laces are cited merely as one example.

In the accompanying drawings a preferred embodiment of mechanism useful in performing my improved process is illustrated by way of example. In the drawings.

Fig. 1 is a diagrammatic plan view illustrating the steps in the complete process;

Fig. 2 is a side elevation of the preferred apparatus, certain parts being omitted and certain parts being in section or broken away, but showing the general relation of the presenting means, the reeling means, the transferring means and the wrapping means;

Fig. 3 is a fragmentary plan view of the parts shown in Fig. 2;

Fig. 4 is a fragmentary perspective showing parts of the transferring and wrapping devices;

Fig. 5 is a fragmentary plan view, partly in section, showing one form of reservoir conveyor for presenting the articles to the reel, most of the remainder of the machine being omitted;

Fig. 5a is a fragmentary side elevation of the parts shown in Fig. 5, many parts being omitted;

Fig. 6 is a fragmentary horizontal section on the line 6—6 of Fig. 5a showing a portion of the drive mechanism for the article-presenting means;

Fig. 6a is a fragmentary plan view showing lace separating means preferably associated with the presenting means of Fig. 5;

Fig. 7 is a fragmentary side elevation from the same side of the machine as Fig. 2, but to larger scale, showing the reel and associated parts in position to receive an article to be wound;

Fig. 8 is a fragmentary side elevation from the opposite side of the machine from Fig. 7 showing the reel in winding position and the transferring means in the act of moving a previously wound pair of laces away from the reeling means;

Fig. 9 is a view generally similar to Fig. 8 but showing the parts at the completion of the reeling operation and in position for transferring the reeled laces to the transfer device;

Fig. 10 is a view similar to Fig. 9 but showing the parts at the completion of the stripping operation;

Fig. 11 is a fragmentary vertical section substantially on the line 11—11 of Fig. 7 showing a pair of laces as having just been presented to the reel;

Fig. 12 is a section substantially on the line 12—12 of Fig. 8 but to larger scale;

Fig. 13 is a bottom plan view from the position of the line 13—13 in Fig. 11;

Fig. 14 is a horizontal section through the shaft of the transfer device, showing the skein holding elements of the transfer device in plan;

Fig. 15 is a fragmentary section substantially on the line 15—15 of Fig. 11;

Fig. 16 is a fragmentary section substantially similar to Fig. 12 but showing the article gripping means in position for receiving the end of the article to be reeled;

Fig. 17 is a fragmentary section on the line 17—17 of Fig. 16;

Fig. 18 is a vertical section on the line 18—18 of Fig. 7 omitting certain parts for the sake of clearness in illustration;

Fig. 19 is a fragmentary section substantially on the line 19—19 of Fig. 18;

Fig. 20 is a section substantially on the line 20—20 of Fig. 18 but showing the tensioning device in operative position;

Fig. 21 is a section to larger scale substantially on the line 21—21 of Fig. 20.

Referring to the drawings and particularly to Fig. 1, the apparatus comprises broadly a mechanism A adapted to perform a preliminary operation upon the strand-like articles,—for example, if as here specifically described these articles are shoe laces, the mechanism A may be the tipping machine.

The improved apparatus also comprises mechanism B adapted to transfer the laces from the mechanism A to a reeling device C. For purposes of illustration the mechanism B is here disclosed as an endless conveyor adapted to receive and hold a plurality of pairs of laces on their way from the tipping machine A to the winding mechanism C. This conveyor in its preferred form constitutes a storage reservoir adapted to receive and hold a large number of pairs of laces. However, in its broader aspects the invention contemplates the provision of other means for transferring laces from the tipping machine A to the reeling means C and such transferring means may or may not provide storage for a plurality of pairs of laces. For example the means B may provide for transferring a single lace or pair of laces directly from the tipping machine to the reeling means.

The improved apparatus further provides a transfer device D which receives the coiled laces from the winding means C and which transfers such coiled laces to a wrapping mechanism designated by the letter E. Preferably the transfer mechanism D is so designed that while it is receiving a pair of coiled laces from the reeling means C, it may simultaneously deliver a previously wound pair of laces to the wrapping mechanism. Obviously, so far as its broader aspects are concerned, certain of the devices A, B, etc., might be combined in a single unit. For example, the transfer D and wrapping device E may be so combined.

The several mechanisms C, D, E are preferably mounted upon a common table or support 1 provided with suitable legs 2, and this table also supports part at least of the mechanism B. If desired the mechanisms A and B may be wholly mounted on this table or support 1 but ordinarily the mechanism A will have an independent base which will carry one end of the mechanism B.

Without specifically describing the structure of the mechanism A it may be assumed that it is provided with suitable dies or other elements of usual character for applying tips to braided laces, for example as shown in either of the patents to Church, 866,916, dated September 24, 1907 or Albracht, 763,832, dated June 28, 1904, and preferably this apparatus is so arranged that the tipped laces are delivered directly to holders or supports forming a part of the storage reservoir or conveyor as hereinafter described. To this end the tipping machine is driven in timed relation to the other parts of the apparatus by suitable drive connections (not shown) leading from shaft 4 hereinafter described. Although such delivery means may be provided, it is contemplated that the operator may by hand take the laces as delivered from the tipping machine or from any other suitable source of supply and insert them in the supports of the storage reservoir.

Reservoir conveyor

Referring now particularly to Figs. 2, 3, 5, 5a, 6 and 6a the frame of the machine is shown as

provided with a supporting bracket 3 having bearings for a main drive shaft 4 provided at one end with a drive pulley 5 receiving power from any suitable source.

5 The mechanism B is here shown as consisting of an endless conveyor chain 6 provided at intervals with outstanding holders or supports 7. These lace supports are preferably furnished with open-ended narrow slots 8 adapted to receive a pair of laces 9, 10, disposed side by side. While the machine is particularly intended for winding flat laces including flat tubular laces such as are illustrated in the drawings, it is equally capable of winding laces of other type. The 15 laces of each pair are inserted in the slot in the corresponding support 7 with the tip at one end of each lace at a predetermined distance below the support 7, (see Fig. 7), this distance being determined by a gauge or other suitable means 20 not shown, provided the laces are inserted in the support 7 by hand. If inserted mechanically the operation of the mechanical positioning means may be such as to place the laces in proper position with one end of each lace depending from 25 the support to the right amount. The opposite ends of the laces hang freely from the support and may trail behind the support as the latter moves forwardly with the conveyor chain. The chain 6 is of sufficient length so that as many 30 pairs of laces as desired may be supported thereon at the same time, thus constituting a storage reservoir.

The chain 6 passes around a sprocket wheel 11 (Figs. 1, 5 and 5a) mounted on a shaft 12 supported in a bracket 13 forming the upper part of a pedestal 13a carried by the table 1. The chain also passes around a suitable guide sprocket 11a (Fig. 1) disposed adjacent to the mechanism A if the latter be employed. A second guide sprocket 40 14 (Figs. 1, 3 and 5) engages the chain at a point near the sprocket 11 and is adapted to cause one run of the chain to diverge from parallelism with the other run so as to bring the supports into proper delivery relation to the winding means. 45 The sprocket 14 is mounted upon a stub shaft 15 also carried by the bracket 13. A gear 16 is secured to the upper end of shaft 12 so as to turn therewith and meshes with a pinion 16a on a stub shaft 16b carried by the bracket 13. A 50 sprocket 17 is secured to the shaft 16b or directly to pinion 16a and a chain 18 passes around the sprocket 17 and also about a sprocket 19 carried by an intermittently driven shaft 110 hereafter described.

55 *Tensioning means*

At a point near the delivery end of the conveyor chain suitable tensioning and separating means is provided, this being shown particularly in Figs. 60 2, 3, 5, 5a, 20 and 21.

Referring to Fig. 5a, the numeral 20 designates a standard provided at its upper end with bearings for the reel shaft as hereinafter described. This standard 20 supports a bracket 21 having a trough-like supporting surface 22 (Figs. 2, 5, and 65 11) at its outer end. This trough-like surface is of a width such as to accommodate a pair of laces disposed in edge to edge relation and is furnished with upstanding flanges at its edges to prevent 70 accidental escape of the laces. This supporting surface 22 is preferably inclined downwardly as indicated in Fig. 5a and from the center of the lower edge of this surface an elongate separating finger 23 depends. This finger preferably consists of a length of stiff wire or rod which reaches

along the path of the conveyor (Fig. 5) to any desired extent, for example to the receiving end of the conveyor, and which lies in the vertical plane of the line of division between the laces of a pair as they move along with the conveyor chain. This finger 23 is adapted to enter between the trailing ends of the laces of the pair and to keep the latter separated as they are drawn across the surface 22 by the movement of the support 7. As indicated in Fig. 5 the supporting surface 22 is so disposed that the trailing ends of the laces are certain to engage such surface as the laces approach the reeling position.

Since it is difficult to support the thin wire finger 23, if of substantial length, I prefer to employ the arrangement shown in Figs. 5 and 6a. In accordance with the preferred arrangement the finger 23 terminates a relatively short distance from the bracket 21 but its separating function beyond its terminus is performed by means of a fence comprising a chain of gate members supported below (Fig. 5a) and substantially in the vertical plane of the loaded run of the chain. These gate members are arranged in pairs, each pair comprising a stationary member 23a supported at one end and having a hook at its other end, and a spring pressed swinging member 23b pivotally supported at one end and having a pin at its opposite end normally engaging the hook at the end of member 23a. The gate members 23a and 23b are normally in alignment, and the successive pairs of gate members constitute a continuous fence separating the laces 9 and 10 of a pair as the latter move along with the conveyor. With this arrangement it is possible to pass the depending end of one of the laces of a pair, for example lace 10, transversely through the fence by swinging one of the gate members 23b as indicated in broken lines in Fig. 6a said member automatically returning to normal position under the action of its spring 23c to complete the continuity of the fence as soon as it is released. This type of fence is of especial utility in feeding the laces mechanically to the holder 7 since the laces may be positioned without the necessity of elevating one lace of the pair to drop it over the fence.

If desired the wire finger 23 may be dispensed with and replaced by the end most gate 23a of the series.

The supporting surface 22 forms one element of lace tensioning means, such tensioning means also comprising a movable element now to be described, reference being had especially to Figs. 3, 7, and 20. The numeral 24 designates a bracket 133 extending horizontally from the upper part of the standard 20 and which carries a stub shaft 25 (Fig. 7) supporting a lever arm 26. This lever arm is provided with a rearwardly extending toe 27 connected by a link 28 to a bracket 29 secured to a vertically sliding bar 30. This bar moves in a guideway formed in a boss 31 forming a part of or attached to the table 1. The upper end 32 of the bar 30 preferably projects upwardly beyond the point of attachment of the bracket 29 and forms centering means for a compression spring 33 which bears at its lower end against the bracket 29 and at its upper end against a convenient fixed part, for example the bracket 21.

The lower end of the bar 30 projects down 113 through an opening in the table 1 and its lower extremity rests upon the edge of a plate cam 34. Referring more particularly to Figs. 13 and 20, this cam 34 is shown as having arcuate dwell portions 35 and 36 connected at their opposite ends 111

by cam slopes 37 and 37^a. Preferably this cam is furnished with slots 34^a for the reception of bolts 34^b which secure it to a disk 34^c (Fig. 18) fixed to shaft 38. By thus mounting the cam 34, 5 it is possible to adjust it to obtain the proper timing.

The shaft 38 is provided with a bevel gear meshing with a bevel gear carried by a shaft 39 mounted in suitable brackets carried by the table 1 and 10 which is driven through bevel gears by a vertical shaft 40 (Fig. 2) mounted in the bracket 3. The shaft 40 is provided with a worm wheel 41 driven by a worm 42 on the drive shaft 4. The connections thus described cause the cam 34 to rotate 15 slowly but in a continuous manner during the operation of the machine.

The free or forward end of the arm 26 is furnished with a spring housing 243 (Fig. 21) having a cylindrical bore for the reception of a slide 20 member 244 provided at its lower end with a contact shoe 244^a adapted to engage the laces resting upon the surface 22. This contact shoe 244^a may be of any suitable material according to the 25 degree of friction which it is desired to impose upon the laces.

The member 244 is provided with a stem 246 passing through an opening in the top of the housing 243 and this stem is encircled by a coiled compression spring 247 within the housing. This 30 spring tends to move the shoe 244^a downwardly and this movement is limited by a nut 248 engaging the screw-threaded upper end of the stem 246.

When the lower end 30^a of the rod 30 engages 35 the cam dwell 35 the arm 26 occupies the position shown in Fig. 7, but when the revolution of the cam 34 brings the surface 36 into engagement with the end of the rod 30 the arm 26 is swung downwardly, bringing the shoe 244^a into resilient 40 contact with the laces resting upon the surface 22. The spring 247 is so adjusted as to produce the desired tension upon the laces while they are being wound upon the reel.

45

Reeling means

The reeling means C comprises a hollow axially movable shaft 43 (Figs. 7, 9 and 12) journalled in bearings in the upper part of the standard 20 as above referred to. This hollow shaft 43 50 is provided with a disk-like stop flange 44 adapted to engage the rear end of the shaft bearings in standard 20 and thus to limit axial movement of the shaft in a forward direction. To the rear of the flange or disk 44 the shaft 43 is furnished 55 with an elongate pinion 45. The forward end of the shaft 43 carries a reel comprising the elongate back member 46 (Fig. 12) fixedly secured to the shaft 43.

Referring particularly to Figs. 3, 12, 16 and 17, 60 this back member 46 of the reel is provided at its opposite ends with forwardly projecting reel arms preferably of like character and each comprising separable jaw members 47 and 48. These jaw members project forwardly through an elongate 65 curved slot 49 near the end of the back member 46 and are carried respectively by the upper ends of levers 50 and 51 (Fig. 12) pivotally supported upon a pin 52 secured to the back member 46. The levers 50 and 51 are provided respectively 70 with depending legs 50^a and 51^a which extend toward the shaft 43 and preferably across an opening 53 in the back member 46. A fixed cam 54 projects forwardly from the upper part of the standard 20 and this cam is furnished with a 75 beveled surface 54^a (Fig. 17) at its forward end

adapted in one axial position of the shaft 43 to enter between the legs 50^a and 51^a and thus to separate the jaw member 47 from the jaw member 48. Normally these jaw members are held in gripping relation by means of a spring 52^a engaging the leg 51^a and the lever 50. 80

Since the forwardly projecting reel arm at the opposite end of the back member 46 is preferably of identical construction with that just described, detailed description of said second arm 85 is unnecessary.

When the gripper jaw member 47 is separated from the jaw member 48 a space 55 (Figs. 3 and 16) is provided between them for the reception of the depending short ends of a pair of laces presented by one of the moving supports 7 of the reservoir device. As shown in Fig. 3, the path of travel of the support is such that when the reel occupies the receiving position shown in this figure, the short advancing ends of the laces carried by the support are caused to depend in the vertical plane of the slot or space 55 between the jaw members of the upper reel arm. 90

A bracket 56 (Figs. 3, 11, and 18) projects laterally from the frame and this bracket is furnished with an arcuate slot 57 (Fig. 11) in which a stub shaft 58 is adjustably secured. This shaft 58 carries a large gear 59 which meshes with the elongate pinion 45 on the shaft 43. The gear 59 is adjustably connected by bolts 59^a (Fig. 3) to 100 the hub 60 of a mutilated gear 61. The adjustable connection of gear 59 to the hub 60 permits the reel to be centered accurately relatively to the cooperating parts. The gear 61 is provided with diametrically opposed blank spaces or 110 dwells 62 and meshes with a second mutilated gear 63 having a single dwell portion 64 of substantially semi-circumferential extent. The gear 63 is mounted upon a shaft 65 turning in suitable bearings 65^a in the frame and provided with a 115 bevel gear 66 meshing with a bevel gear 67 carried by a shaft 68 turning in a bearing boss supported by the table 1.

The shaft 68 projects down through the table 1 and is provided at its lower end with a bevel 120 gear 70 meshing with a gear 71 on a shaft 72 mounted in bearings 73 and 74 supported by the table. The shaft 72 is provided with a gear 75 meshing with a gear 76 on the shaft 39 above described. The shaft 72 thus turns continuously 125 during the operation of the machine, but the shaft 43 is turned intermittently through the action of the gears 61 and 63. The latter are so constructed that for each half revolution of the shaft 72 the large gear 59 makes a half revolution and 130 then dwells during the remainder of the revolution of the shaft 72.

The gear 59 bears such a ratio to the gear 45 that a half revolution of the gear 59 suffices to turn the shaft 43 the exact number of times necessary to reel a pair of laces. To permit laces of different lengths to be reeled, the gear 59 may be interchanged with other gears of different diameter, the slot 57 in the bracket 56 permitting such change. 140

The stop disk 44 carried by the shaft 43 is furnished at diametrically opposite points with recesses 76 and 77 respectively, (Fig. 18). A locking dog 78 (Figs. 7 and 18) is mounted to slide vertically in bearings 79 carried by the standard 145 20 and the upper end of this dog is adapted to engage one or the other of the recesses 76 and 77 and thus positively to lock the shaft 43 against rotation with the reel properly centered. The recesses 76 and 77 are disposed in the vertical 150

plane of the back member 46 of the reel so that whenever the dog 78 engages one of the recesses in the disk the reel is held in vertical position with one of its coil supporting arms at the extreme uppermost position.

The locking dog 78 is encircled by a spring 80 bearing at one end against one of the guides 79 and at its other against an adjustable collar 81 secured to the dog. This spring tends to raise the dog 78 and to hold it in locking position.

Referring to Figs. 18 and 19 the lower end of the dog 78 is shown as passing down through a guide opening in the table 1, and at a point somewhat above the table the dog is furnished with a bracket 82 carrying a laterally projecting stud 83 engaging the forked rear end of a lever pivotally supported at 85 upon the standard 20. The opposite end of this lever is also forked and receives a stud 86 projecting from a vertically sliding rod 87 passing down through a suitable guide opening in the table 1. The lower end of the rod 87 rests against the edge of a plate cam 88 (Fig. 19) having dwell portions 89 and 90 connected by active cam surfaces. When the rod 87 engages the dwell 89 the spring 80 raises the locking dog 78 for engagement with one of the recesses 76 or 77 (Fig. 19), but when the rod 87 engages the dwell 89 the locking pin is retracted and occupies the position shown in Fig. 18.

The cam 88 is secured to the disk 34^c attached to the shaft 88 above described and preferably the cam is adjustably connected to the disk 34^c by means of bolts 92 (Fig. 18).

Stripping means

Within the hollow reel shaft 43 is arranged a stripper shaft 94 (Figs. 3, 7, 10 and 12) which is adapted to rotate with the shaft 43 and also to slide axially relative thereto. The shaft 94 is provided at its inner end with a stripper plate 46^a (Fig. 10) which normally engages the forward face of the back plate 46 of the reel and which is furnished with openings for the passage of the reel arms. The rear end of the stripper shaft 94 is furnished with a fixed collar 95 (Figs. 3 and 8) having a circumferential groove 96 adapted to receive oppositely directed pins 97 projecting inwardly from fork arms at the upper end of a lever 98 (Fig. 8). The arrangement just described permits rotation of the shaft 94 but constrains the shaft to move axially with the lever 98.

A coil spring 99 encircles the shaft 94, bearing at one end against the collar 95 and at its other against the rear end of the pinion 45. The lever 98 is pivoted at the point 100 upon a bracket 102 secured to the table 1. The lever 98 has a downwardly directed arm 101 connected by a spring 101^a to the frame of the machine, the spring tending to swing the lever 98 so as to move the shaft 94 rearwardly. The lower arm 101 of the lever is furnished with a forwardly projecting toe 103 carrying a cam follower roll 104 which engages the edge of a plate cam 105. This cam is provided with a low dwell portion 106, a dwell portion 107 somewhat higher than the portion 106, and a still higher part 108. This cam is adjustably secured by bolts 105^b to a disk 105^a mounted on shaft 38 (Fig. 18), said bolts passing through arcuate slots (not shown) in disk 105^a and into threaded holes in the cam 105.

Transfer means

The transfer means D comprises a tubular standard 109 (Figs. 2, 3, 7 and 14) mounted upon the table 1 and providing a bearing for the lower

part of the shaft 110 hereinabove referred to. The upper part of this shaft is received in a tubular bearing 111 depending from a bridge member 112 having legs at its opposite ends which are mounted upon the table 1. The hub 113 (Fig. 8) of a rotary transfer turret is mounted between the upper end of the standard 109 and the lower end of the bearing 111 and is secured to the shaft 110 in any desired manner. This hub 113 carries a plurality of radially projecting arms, four such arms 114, 115, 116 and 117 (Figs. 3 and 14) being shown herein. Each of these arms is provided with a radial bore or guideway for the reception of a shaft 118 which is prevented from rotating in the bore by means of a key 119 (Fig. 8). Each shaft 118 is furnished with a retracting spring 120 (Fig. 14) secured at one end to a pin 121 projecting from the corresponding arm and at its opposite end to a pin 122 projecting from the shaft. The inner end of each shaft 118 is furnished with a beveled cam face 123 terminating in an abrupt shoulder or drop 124. The beveled ends 123 of the several shafts are adapted to engage a cam 124^a secured to the lower end of the bearing sleeve 111, the arrangement being such that as the turret revolves the beveled surfaces 123 of the shafts 118 ride up successively onto the cam 124^a and after reaching a certain point drop suddenly from the latter, thereby permitting the spring 120 to retract the shaft which has been moved radially outwardly in its bearing by the action of the cam 124^a.

The outer end of each of the shafts 118 is furnished with an elongate coil holder 125 (Figs. 3, 110, 8, 10 and 14) of substantially the same length as the rear member 46 of the reel. This coil holder is furnished near its opposite ends with coil supporting arms each preferably consisting of a pair of spaced members 126 and 126^a providing 115 between them a slot 127 (Fig. 14) of a width sufficient to receive the inner ends of the laces as they are stripped from between the jaws of the reel. The coil supporting arms of the coil holder 125 are spaced apart substantially the same distance as the arms of the reel.

The shaft 110 which carries the turret projects down below the table 1 (Fig. 11) and is furnished with a wheel 128 (Figs. 11 and 13) forming one element of a Geneva intermittent drive mechanism. The complementary element of this Geneva drive is indicated at 129, such element being mounted upon the lower part of the shaft 68. Preferably the member 129 is secured to a disk 130 (attached to the shaft 68) 120 by means of bolts 132 projecting through arcuate slots 131 in the disk and enter threaded holes in the member 129. The member 129 may thus be adjusted relatively to the shaft 68 to obtain the desired timing of the parts.

The wheel 128 has four dwell portions corresponding to the four arms of the turret and the parts are so arranged that the turret turns intermittently and when standing still always presents one of its coil holders in receiving position 140 and the diametrically opposite coil holder in a position such as to present its coil to the wrapping mechanism.

Each coil holder 125 is provided at its trailing edge with spaced bearings 133 (Fig. 7) in which a rotary shaft 134 is mounted. At its upper end the shaft 134 is furnished with a laterally projecting clamping arm 136 which is adapted to engage the coil mounted upon the arms of the coil holder and to confine the free outer ends of 145

the laces forming the coil. A spring 135 secured to and encircling the lower part of the shaft 134 is so tensioned as to tend to rotate the shaft 134 in a clockwise direction as viewed from the top, thus causing the arm 136 to press forcibly upon the outer free ends of the lace. A stop block 134^a, having a face which is normally spaced from, but which may come into contact with the adjacent surface of the edge of the coil holder 135 when the shaft 134 turns through a sufficient angle, is secured to the shaft 134 and limits movement of the latter by the spring 135. A contact plate 137 (Fig. 11) supported upon a bracket arm 152 hereafter described is engaged by the end of the arm 136 as the turret revolves toward coil receiving position and thus holds the arm 136 in an inoperative position until just before the turret stops.

The stripper plate is provided with elongate slots 138 (Fig. 12) and when the arm 136 is disengaged from plate 137 by movement of the latter as hereafter described, the arm 136 snaps into the uppermost slot 138 and is thus permitted to swing into operative engagement with the coils, thus confining the free or outer ends of the coils.

Pressing means

In order to confine the laces during winding and to ensure the winding of each lace to form an independent coil or skein suitable pressing means is provided.

This pressing means comprises a horizontally sliding base member 140 (Figs. 3, 8, 11 and 15) mounted to slide between guide members 140^a and 140^b (Fig. 3) secured to the upper surface of the table 1. The slide member 140 carries an upstanding boss 141 having a journal opening for the lower end of a rotatable post 142. An actuating rod 143 is connected at one end to the boss 141 and its other end is guided in a suitable guideway in a block 144 secured to the table 1. A tension spring 145 is attached at one end to the slide member 140 and at its other to a pin carried by the block 144. Preferably the spring 145 extends into a bore in the block 144 for the sake of economy in space.

The free end of the actuating rod 143 engages the edge of a plate cam 146 (Figs. 3 and 11) mounted on the shaft 65 above described. This cam rotates continuously during the operation of the machine and comprises a dwell portion 146^a, a riser portion 146^b, and a second dwell 146^c, the latter being followed by an abrupt drop.

A cam arm 147 (Figs. 11 and 15) is fixedly secured to the shaft or post 142 and engages an adjustable stop pin 148 mounted in a bracket 149 carried by the guide member 140^a. A spring 142^a (Fig. 11) encircling the post 142 tends to turn the latter so as to keep the cam arm 147 always in contact with the stop member 148.

The upper end of the post 142 carries a bracket 151 supporting the overhanging arm 152 above referred to. This arm 152 is provided at its outer end with a pressure shoe 153. This shoe is furnished with an arcuate lower surface 155 (Fig. 11) adapted to engage the coil upon the reel while the latter is rotating and this shoe is resiliently cushioned by means of suitable springs 154.

Wrapping means

The wrapping mechanism may be of any suitable type but is here shown merely by way of example as comprising a casing 157 (Figs. 2, 3 and 4) mounted on the table 1, and containing a

drive shaft 158 which is driven by a beveled gear 159 (Fig. 2) on the upper end of the shaft 40. The casing also supports an arm carrying a support for a coil of wrapping paper 160, the paper strip passing into the casing and over a guide pulley 161. The inner face of the casing 157 is furnished with a recess 162 (Fig. 2) adapted to receive the coil holder of the turret as the latter swings into its delivery position.

Within the recess 162 are mounted the sliding die members 163 and 164 (Fig. 4) whose opposed ends are adapted to engage a portion of the paper strip and to carry it around the coiled laces mounted upon the coil holder. A knife 166 mounted in a suitable guide 167 is adapted to cut off a suitable length from the paper strip just prior to the approach of the die members 163 and 164. The paper strip may be provided with adhesive in any suitable way and after the die members have wrapped the severed portion of the paper about the coil on the coil holder, the wrapped coil may be stripped from the coil holder by hand or by any suitable stripper mechanism. Such stripper mechanism may be conveniently located to act upon the coil holder when the latter has made quarter revolution beyond the wrapping point. Since the stripping may conveniently be performed by hand no stripping mechanism has herein been shown.

Operation

The operation of the mechanism as a whole is briefly as follows; it being assumed that the drive shaft 4 is in continuous rotation.

If the mechanism A is a tipping machine it is assumed that this machine is in operation, applying tips to the shoe laces and that as the tips are applied each successive pair of laces is entered into the slot in one of the supports 7 of the conveyor chain or reserve supply. As above stated this entry of the pair of laces into the slot may be performed by hand, or mechanically, delivery means such for example as that disclosed in the patent to Church, supra, being generally adapted for the purpose. The laces forming a pair are placed in the slot 8 side by side and with the tip at one end of each lace depending below the support 7 a distance usually somewhat less than one half the length of the coil to be formed. The chain 6 is driven intermittently so that the supports 7 advance step by step toward the reeling means.

As a support with its pair of laces approaches the reeling position the trailing ends of the two laces which have been moving along upon opposite sides of the fence, come into engagement with opposite sides of the separator finger 23 so that as the laces are dragged across the support 22 they are kept separate and in proper relation.

As the support 7 with its pair of laces approaches the reeling position the gears 61 and 63 reach such a relative position that the gear 59 is stopped with the back member 46 of the reel in vertical position as indicated in Figs. 3, 7, or 11. At the same time the rotation of the cam 105 has brought the cam follower roll 104 onto the lowest part of the cam, and the spring 101^a has moved the lever 98 and thereby the shaft 43 to its extreme rearward position, (Fig. 7). As the shaft 43 assumes this extreme rear position the cam 54 enters between the legs 50^a and 51^a of the pincer-like device carrying the jaw members 47 and 48 of the uppermost reel arm, thus moving the jaw 47 away from the jaw 48 to pro-

vide the space 55 necessary for the reception of the dependent ends of the laces. The depending ends of the laces supported by the support 7 now occupy the position indicated in Fig. 5 where they 5 are in the vertical plane of the space between the jaws 47 and 48.

The cam 105 continuing to rotate causes the roll 104 to ride up onto the dwell surface 107. During this motion the shaft 43 is advanced forwardly, thus causing the jaws 47 and 48 to pass upon opposite sides of the depending ends of the laces and as the roll 104 comes into engagement with the dwell 107 (Fig. 8) the jaws 47 and 48 are released from the cam 54 so that the jaw 47

15 approaches and the jaw 48 securely clamps the depending ends of the laces between them. The forward movement of the shaft 43 is limited by engagement of stop disk 44 with the standard 20. While the cam follower roll 104 engages the dwell 20 107, the rod 87 (Fig. 19) engages the dwell 89 of the cam 88, thus retracting the pin 78 from the disk 44 so as to permit free rotation of the shaft 43.

At about the same time that the roll 104 rides up onto dwell 107 of cam 105, the rotation of the cam 25 34 causes the lower end 30^a of the rod 30 to ride up from the dwell 35 of cam 34 onto the dwell 36, thereby swinging the tension arm 26 downwardly until its shoe 244^a presses firmly against trailing ends of the laces lying upon the surface 22.

30 Before the above operations, the rotation of the cam 146 has permitted the actuating rod 143 to move quickly to the right as viewed in Figs. 11 and 15 under the action of spring 145, thus permitting the arm 147 to assume the dotted line 35 position of Fig. 15, and bringing the shoe 155 into position to engage the outer surface of the winding coils shortly after the reel begins to turn. As the coil or skein builds up its outer layers engage the spring pressed shoe 155 which smooths the 40 layers and holds them in proper relative position.

The various cam followers previously described now travel upon dwells of their respective cams during the winding operation. This winding is initiated by engagement of the teeth of the gear 45 63 with a toothed portion of the gear 61, thus rotating the gear 59 (Fig. 11) a half revolution and thereby spinning the shaft 43 a sufficient number of turns to wind the entire length of the laces upon the arms of the reel. When the laces 50 have thus been reeled, the gear 61 again comes to rest and at about this time the Geneva motion turns the turret a quarter revolution. As the reeling operation is completed, the cam follower roll 104 rides up onto the high part 108 of the cam 55 105, thus swinging the lever 98 forwardly. At about this time the rod 87 (Fig. 19) drops from the dwell 89 onto the dwell 90 thus permitting the spring 80 to lift the locking pin 78 into engagement with one of the notches of the disk 44. The back member 46 of the reel is thus held in substantially vertical position and directly opposite to one of the coil holders 125 of the turret, the arms of the reel being aligned with the arms of the coil holder, the ends of such arms being spaced 60 but a short distance apart.

As the lever 98 is moved forwardly by the cam riser 108 the spring 99 is compressed, forcing the stripper shaft 94 forwardly relative to the shaft 70 43. The stripper plate 46^a thus moves forwardly away from the back member 46 of the reel and pushes the coiled laces from off the arms of the reel onto the arms of the coil holder. In Fig. 9 the parts are shown in position for this transfer, and in Fig. 10 the parts are shown at the comple-

tion of the transfer and just prior to the rearward movement of the stripper plate 46^a.

During the forward movement of the stripper plate, the actuating rod 143 is moved by the riser 146^b of the cam 146 and through the action of the cam arm 147 and the stop pin 148 swings the post 142, thus causing the presser shoe 155 to remain in contact with the outer coils of the skein during the transfer operation. Toward the end of this movement the plate 137 releases the clamping arm 136 of the coil holder of the turret, permitting the latter to snap into engagement with the ends of the coiled laces.

As soon as the transfer has been completed the cam follower roll 104 rides down off of the high part of the cam 105, thus permitting the spring 101^a to move the shaft 43 with the reel and transfer plate rearwardly into the receiving position and the gripper jaws are again opened by the cam 54. The rod 143 now rides up onto the upper 90 dwell of cam 146 where it remains until the next winding operation. The coiled laces are thus left upon the arms of the coil holder in the turret with their inner ends in the slot in the arm of the coil holder of the transfer turret and with their 95 outer ends confined by the arm 136.

It being assumed that pairs of laces have previously been coiled and applied to the coil holders of the transfer turret, one of such holders with its coiled pair of laces will occupy the position 105 shown in Fig. 4, relatively to the wrapping mechanism, during the time that a pair of laces is being transferred to the diametrically opposite holder as above described. As the turret turns to bring a coil holder into wrapping position, the 110 cam 124^a pushes the corresponding shaft 118 radially outward so as to thrust the loaded coil holder 125 into the space between the opposed dies 163 and 164. The knife 166 now severs a portion from the paper strip and the dies move 115 inwardly toward each other, thus wrapping the paper strip about the coiled laces held by the arms of the coil holder. During this wrapping operation the arm 136 continues to hold the free ends of the laces in confinement so that they 120 can not escape during the wrapping operation. The paper wrapper is of sufficient width to embrace these free ends of the laces and after the wrapping operation is completed the coiled laces may be stripped from the arms of the coil 125 holder in any desired manner without danger that the ends of the laces will be released.

As above stated the stripping of the wrapped laces from the coil holder after the wrapping operation may be performed by hand or by any 130 suitable mechanical means not shown.

While I have herein disclosed certain specific arrangements of parts for securing the desired result, I contemplate that other and equivalent means may be substituted therefor if desired, that 135 the parts may be arranged differently, and that in some cases certain parts may be omitted and so far as the process is concerned I contemplate that various of the process steps may be omitted or that the order of such steps may be varied 140 without departing from the spirit of the invention.

I claim:

1. Apparatus for packaging shoe laces comprising reeling means, and endless conveyor 145 means adapted to receive laces from a lace tipping machine and automatically to present them to the reeling machine.

2. Apparatus for packaging independent strand-like articles comprising means for reel- 150

- ing such articles to form flat coils, an endless conveyor having spaced means for holding said articles, and means for moving the conveyor to present said spaced articles successively to the reel means. 5
3. Apparatus of the class described comprising means for simultaneously reeling a pair of independent strand-like articles, a reservoir comprising an endless conveyor having means for 10 simultaneously supporting a plurality of pairs of said articles, and means for advancing said conveyor intermittently whereby successively to present the pairs of articles to the reeling means.
4. Apparatus for packaging flat strand-like articles which comprises means for reeling such an article, an endless conveyor, a support carried by the conveyor providing a narrow open-ended slot into which such an article may be slipped edgewise, and means for moving the conveyor to carry the support into proximity to the reeling means so that an article held in the slot in the support may be operatively engaged by the reeling means. 15
5. Apparatus of the class described comprising means for simultaneously reeling a pair of independent strand-like articles, a reservoir comprising an endless conveyor having spaced supports each provided with means for releasably supporting a pair of said articles, and means for 20 moving the conveyor to present each pair of articles in succession to the reeling means.
6. Apparatus of the class described comprising means for simultaneously reeling a pair of strand-like articles, a reservoir comprising an endless conveyor having spaced supports each provided with means for releasably supporting a pair of said articles, with their ends depending, means for moving the conveyor to present each pair of articles in succession to the reeling means, 25 and means for keeping separate the depending ends of the articles of the pair.
7. Apparatus of the class described comprising means for simultaneously reeling a pair of strand-like articles, a reservoir comprising an endless conveyor having spaced supports each provided with means for releasably supporting a pair of said articles, with their ends depending, means for moving the conveyor to present each pair of articles in succession to the reeling means, 30 and a fence extending longitudinally of the conveyor and adapted to separate the depending ends of the laces of a pair as they move with the conveyor.
8. Apparatus of the class described comprising means for simultaneously reeling a pair of strand-like articles, a reservoir comprising an endless conveyor having spaced supports each provided with means for releasably supporting a pair of said articles, with their ends depending, 35 means for moving the conveyor to present each pair of articles in succession to the reeling means, and a fence extending longitudinally of the conveyor and adapted to separate the depending ends of the laces of a pair, said fence comprising pivoted gates adapted to admit the depending end of a lace to be passed from one side of the fence to the other. 40
9. Apparatus of the class described comprising means for simultaneously reeling a pair of strand-like articles, a reservoir comprising an endless conveyor having spaced supports each provided with a slot adapted to receive a pair of said articles with their ends depending, and 45 means for moving the conveyor whereby successively to present said pairs of articles to the reeling means.
10. Apparatus for packaging strand-like articles comprising a rotary reel provided with article gripping devices, a conveyor moving in a path intersecting the plane of rotation of the reel, said conveyor having a support for an article to be reeled, and means for so relatively moving the conveyor and the article gripping devices of the reel as first to bring the article into engagement with the gripping devices and then to disengage it from the support. 50
11. Apparatus for packaging flat shoe laces in pairs comprising means for simultaneously reeling a pair of such laces, a conveyor, a support carried by the conveyor having an open-ended recess adapted to receive the laces edgewise and from which they may be withdrawn by movement endwise of the slot, means for moving the support in a path such that one end of each lace is operatively engaged with the reeling means, and means for relatively moving the support and reeling means to disengage the laces from the slot. 55
12. Apparatus for packaging strand-like articles comprising a reel rotating in a vertical plane and having article gripping jaws, a conveyor having an article support moving in a substantially horizontal path intersecting the plane of movement of the gripper jaws, means for moving the article support to present an article carried thereby to the gripper jaws, and means for thereafter causing the article support and gripper jaws relatively to diverge to disengage the article from the support. 60
13. Apparatus for packaging strand-like articles comprising a rotary reel having article gripping jaws, an article support movable in a path above the gripping jaws, said support having means for releasably retaining the strand-like articles with one of its ends depending, means for moving said support to present the depending end of the article to the gripping jaws, and means for closing the jaws and for moving the jaws relatively to the support to pull the article from out of the releasable retaining means. 65
14. Apparatus for packaging strand-like articles comprising a rotary reel having article gripping jaws, an article support having an open-ended slot adapted to receive such a strand-like article with one of its ends depending, means for moving said support in a path such that the depending end of the article is presented to the gripping jaws, and means for closing the jaws upon said end and for relatively moving the support and gripping jaws to cause said article to move endwise of the slot in the support whereby to be released from the latter. 70
15. Apparatus for packaging strand-like articles comprising a reel, a rotary and axially movable shaft supporting the reel, and means for shifting the shaft axially to dispose the reel in article receiving position and in winding position, respectively. 75
16. Apparatus for packaging strand-like articles comprising a reel, a rotary and axially movable shaft supporting the reel, means for shifting the shaft axially to dispose the reel in article receiving and winding positions, respectively, a notched collar secured to the shaft constituting a stop to limit axial movement of the shaft, and a dog engageable at predetermined times with a notch in said collar to prevent rotation of the reel. 80
17. Apparatus for coiling shoe laces comprising

- ing a rotary reel provided with lace gripping means arranged to rotate in the plane of the coil to be formed, means for rotating the reel intermittently, and means for introducing one end 5 portion of a shoe lace into the gripping means in the interval between periods of rotation.
18. Apparatus for coiling independent strand-like articles comprising a reel on which the articles are coiled, means for turning the reel intermittently and for bringing it to rest in the interval between successive periods of rotation in one of two predetermined angular positions, and means for presenting one end portion of a strand-like article to the reel, the reel comprising means 10 arranged to turn in the plane of the coil to be formed and which, in either of said angular positions of rest, is disposed to receive the strand-like article.
19. Apparatus for packaging strand-like articles comprising a reel having a plurality of arms each provided with article gripping jaws, means for presenting a strand-like article to the reel, and means for intermittently rotating the reel and for stopping it in each interval between periods of rotation in such an angular position that one of the gripping means may receive an article from the presenting means.
20. Apparatus for packaging tipped laces comprising a shaft, means including a pair of mutilated gears for rotating the shaft intermittently, a reel carried by the shaft, said reel having article holding means, means for presenting a lace to the holding means of the reel and for guiding the lace as the reel rotates whereby to wind the lace in a flat coil.
21. Apparatus for packaging tipped laces comprising a shaft, means including a pair of mutilated gears for rotating the shaft intermittently and for stopping the shaft in a definite angular position at intervals, a reel carried by the shaft, and means for presenting a lace in operative relation to the reel during one of the periods in which the shaft is stopped.
22. Apparatus for packaging laces comprising a reel having a pair of diametrically opposite arms each provided with lace gripping jaws, means comprising mutilated gears for intermittently rotating the reel, one or the other of said arms being disposed in article receiving position during successive intervals between periods of rotation, means for presenting a lace to either of said arms while it is in receiving position and for guiding the lace during rotation of the reel whereby to produce a flat coil.
23. Apparatus for coiling shoe laces comprising a reel, and means for rotating the reel in the plane of the coil to be formed, means for presenting a shoe lace to the reel to be coiled thereon, a stripper member carried by the reel and rotating therewith, and means for moving the stripper at the end of the coiling operation for stripping the coiled lace from the reel.
24. Apparatus for packaging tipped laces comprising a reel having a back member, arms projecting forwardly from the back member, means for presenting a lace to the reel to be coiled upon the arms, a stripper normally disposed adjacent to the front face of the back member, and means for moving the stripper forwardly to strip the coiled lace from the arms.
25. Apparatus for packing tipped laces comprising a reel having a back member, arms projecting from the back member, means for presenting a lace to the reel to be coiled upon the arms, a hollow shaft supporting the back member,
- an axially movable stripper shaft within the hollow shaft, a stripper carried by the stripper shaft and normally disposed adjacent to the front face of the back member of the reel, and means for moving the stripper shaft to cause the stripper to eject the coiled lace from the reel arms.
26. Apparatus for packaging strand-like articles comprising a reel having a back member, arms projecting from the back member, means for presenting an article to the reel to be coiled upon the arms, a rotary, axially movable hollow shaft supporting the back member of the reel, an axially movable stripper shaft within the hollow shaft, a stripper carried by the stripper shaft, and means for first axially moving the hollow shaft and stripper shaft simultaneously to carry the reel to reeling position, and for thereafter continuing the movement of the stripper shaft alone to strip the coiled article from the reel.
27. Apparatus for packaging strand-like articles comprising a reel having a back member, arms projecting from the back member, means for presenting an article to the reel to be coiled upon the arms, a rotary, axially movable hollow shaft supporting the back member of the reel, an axially movable stripper shaft within the hollow shaft, a stripper carried by the stripper shaft, a cam actuated lever for moving the stripper shaft axially, and a spring for transmitting movement from the stripper shaft to the hollow shaft.
28. Apparatus for packaging strand-like articles comprising a reel having a back member, arms projecting from the back member, means for presenting an article to the reel to be coiled upon the arms, a rotary, axially movable hollow shaft supporting the back member of the reel, an axially movable stripper shaft within the hollow shaft, a stripper carried by the stripper shaft, means including a spring for moving the hollow shaft axially to carry the reel from reeling to reeling position, and a stop limiting such movement of the hollow shaft, said shaft moving means thereafter moving the stripper shaft axially relatively to the hollow shaft to strip the coiled article from the reel arms.
29. Apparatus for packaging tipped laces comprising a rotary reel having lace gripping means, means for presenting one end portion of a lace to the gripping means, and resilient means for applying tension to the article as it is being reeled.
30. Apparatus for packaging strand-like articles comprising a rotary reel having means for gripping a strand-like article near one of its ends leaving the main part of said article depending, means for presenting such an article to the gripping means, a guide for the depending part of the article, and tension means associated with the guide.
31. Apparatus for packaging strand-like articles comprising a rotary reel having means for gripping a strand-like article near one of its ends leaving the main part of said article depending, means for presenting such an article to the gripping means, means alternately holding the reel stationary to receive the article and rotating the reel to coil the article, and means for tensioning the depending part of the article during rotation of the reel.
32. Apparatus for packaging strand-like articles comprising a rotary reel having means for gripping a strand-like article near one of its ends leaving the main part of said article depending, means for presenting such an article to the gripping means, a guide surface for supporting the depending part of the article, and a tension

clamp cooperable with the guide surface to tension the article during operation of the reel.

33. Apparatus for packaging strand-like articles comprising a rotary reel having means for gripping a strand-like article near one of its ends leaving the main part of said article depending, means for presenting such an article to the gripping means, a guide trough for supporting the depending part of the article, and a spring pressed 5 clamping plate for pressing the article against the bottom of the trough to tension it during operation of the reel.

34. Apparatus for packaging strand-like articles comprising a rotary reel having means for gripping a strand-like article near one of its ends leaving the main part of said article depending, means for presenting such an article to the gripping means, means alternately holding the reel stationary to receive the article and rotating the 10 reel to coil the article, means for tensioning the depending part of the article during rotation of the reel, and means for rendering the tensioning means inoperative when the reel is stationary.

35. Apparatus for packaging strand-like articles comprising a rotary reel having means for gripping a strand-like article near one of its ends leaving the main part of said article depending, means for presenting such an article to the gripping means, a guide surface for engagement with 25 the depending part of the article, a tensioning clamp cooperable with said guide surface to tension the article as the reel is operated, said clamp being mounted upon a pivoted lever, and means for swinging the lever to separate the clamp from 30 the guide surface.

36. Apparatus for packaging shoe laces in pairs comprising a rotary reel having means for gripping a pair of laces near one of their ends, means for advancing said laces into position to be gripped by said gripping means, and means for keeping the main portions of said laces separated 40 during such advance.

37. Apparatus for packaging shoe laces in pairs comprising a rotary reel having means for gripping a pair of laces near one of their ends leaving the main portions of said laces depending, means for presenting the laces to the gripping means, means alternately holding the reel stationary to receive the laces and rotating the reel 45 to coil the laces, and means for separating the depending portion of the two laces during rotation of the reel.

38. Apparatus for packaging shoe laces in pairs comprising a rotary reel having means for gripping a pair of laces near one of their ends leaving the main parts of said laces depending, means for advancing the laces to present them to the gripping means, a guide having a surface with which the depending portions of the laces engage, 55 and a separating finger extending from said guide toward the advancing laces to separate the depending portions of the laces as they approach the guide.

39. Apparatus for packaging tipped laces comprising a shaft, means for intermittently rotating the shaft, a reel carried by the shaft, the reel comprising gripper jaws, means for opening the jaws in the interval between periods of rotation of the shaft, and means for introducing a lace 60 between the jaws while the latter are open and for closing the jaws prior to the beginning of the next period of rotation of the shaft.

40. Apparatus of the class described comprising a rotary reel having gripping jaws, means for rotating the reel intermittently and for open-

ing and closing the gripping jaws in the interval between periods of rotation, and means for introducing the end portion of a tipped lace between the jaws while the latter are open.

41. Apparatus for packaging strand-like articles comprising a rotary and axially movable shaft, a reel mounted upon the shaft, the reel comprising relatively movable article gripping members, a spring tending to hold said members in gripping relation, a cam fixed relatively to the shaft, and means for moving the shaft axially to cause the cam to separate the gripping members to permit introducing an article between said gripping members.

42. Apparatus for coiling strand-like articles comprising a reel, means for turning the reel intermittently, the reel comprising a plurality of arms arranged to revolve in the plane of the coil to be formed, each of said arms being provided with article gripping means, and means for presenting one end portion of a strand-like article to the reel, the means for turning the reel being adapted to bring the reel to rest at the end of each period of rotation with one of said gripping means positioned to receive the end portion of 90 said article delivered by the presenting means.

43. Apparatus for packaging strand-like articles comprising a reel having a rotary back member and arms projecting from the back member, one at least of the arms comprising relatively 105 movable gripping members, spring means tending to hold said members in gripping position, a stationary cam device, means to move the back member relatively to said cam device to cause the latter to separate the gripping members, and 110 means for presenting a strand-like article to said separated members.

44. Apparatus for packaging strand-like articles comprising a reel having a rotary back member, parallel arms projecting from the back member, one at least of said arms being longitudinally split to provide opposed gripping members, levers pivoted to the back member, each lever supporting one of said gripper members, a spring tending to hold said members in gripping position, a cam device engageable with the levers for 120 separating the gripper members, and means for presenting an article to the gripper members while they are separated.

45. Apparatus for packaging strand-like articles comprising a reel having a rotary back member, said back member having an opening spaced from its center, a pincer-like device mounted upon the rear side of the back member, said pincer-like device comprising relatively movable 130 levers, a gripper member secured to one end of each of said levers and projecting forwardly through the opening in the back member, said grippers collectively constituting one arm of the reel, means for separating the gripper members 135 constituting the first arm, and means for presenting an article to the separated gripper members.

46. Apparatus for packaging strand-like articles comprising a reel having a rotary back member and arms projecting from the back member, one at least of the arms comprising a pair of relatively movable gripping members, spring means tending to hold said gripping members in gripping position, cam means for separating said 145 members, and means for presenting a strand-like article to said members while they are separated.

47. Apparatus for packaging strand-like articles comprising a reel having a rotary back member, parallel arms projecting from the back mem- 150

- ber, one at least of said arms being longitudinally split to provide opposed gripping members, said members being relatively movable, spring means tending to move said members into engagement, a cam device movable relatively to the back member of the reel for separating said gripping members, and means for presenting a strand-like article to said members when they are separated.
- 10 48. Apparatus for packaging strand-like articles comprising a reel having a rotary back member, said back member having an opening spaced from its center, a pincer-like device mounted upon the rear side of the back member, said 15 pincer-like device comprising relatively movable levers, a gripper member secured to one end of each of said levers and projecting forwardly through the opening in the back member, said grippers collectively constituting one arm of the 20 reel, and a cam device engageable with the opposite arms of said lever for separating the gripper members.
49. Apparatus for packaging tipped laces comprising means for reeling such a lace to form a skein, means for wrapping the skein, and a conveyor adapted to receive and to hold a plurality of skeins successively coiled by the reeling means and to convey them to the wrapping means.
50. Apparatus for packaging tipped laces comprising a reel mounted to rotate about a fixed axis, means for intermittently rotating it and for holding it stationary in delivery position, a device having a plurality of coil receiving means, and means for presenting said coil receiving means 30 successively in position to receive laces coiled upon the reel, and means comprising a stripper device, rotating with the reel, for delivering the coiled laces from the reel to the receiving means of the coil transfer device.
- 40 51. Apparatus of the class described comprising a rotary reel mounted to rotate about a fixed axis and to move longitudinally of said axis, said reel having spaced arms, a transfer device having correspondingly spaced arms, means for relatively 45 moving the transfer device and reel to bring their corresponding arms into alignment, means for moving the reel axially from a coiling to a delivering position and means for stripping the coiled article from the reel arms onto the arms of the 50 transfer device.
52. Apparatus of the class described comprising a reel having a back member and spaced parallel arms carried thereby, a transfer device having correspondingly spaced parallel arms, means for 55 bringing the arms of the transfer device into axial alignment with the arms of the reel, and means for stripping the coiled article from the reel arms onto the arms of the transfer device.
53. Apparatus for packaging tipped laces comprising a rotary reel, mutilated gears for intermittently driving the reel to wind a lace in a flat coil, a rotary transfer turret having coil receiving means, Geneva gearing for intermittently driving the turret, means for shifting the flat coil 60 from the reel to the coil receiving means of the turret, and means for actuating the mutilated gears and Geneva gearing in timed relation.
54. Apparatus of the class described comprising a reel having a plurality of arms, one at least 65 of said arms being divided longitudinally to provide a slot for the reception of the end portion of a strand-like article to be wound, wrapping means, means for transferring the coiled article from the reel to the wrapping means, the transferring means comprising a holder having a plurality of 70 75 arms corresponding to the arms of the reel, one at least of the transfer holder arms having a longitudinal slot in its end for the reception of the inner end portion of the coiled article, means for aligning the slotted arms of the reel and transfer holder, and means for stripping the coiled article from the arms of the reel onto those of the transfer holder and for simultaneously moving the inner end of the coiled article into the slot in the holder arm.
55. Apparatus for packaging strand-like articles comprising a rotary and axially movable reel, a transfer device, means for rotating the reel while in one axial position for coiling the article, means for moving the reel axially to dispose it in delivering position in cooperative relation to the transfer device, means for stripping the coiled article from the reel onto the transfer device, and means for maintaining the relative position of the coils substantially unchanged 80 during the transfer.
56. Apparatus for packaging strand-like articles comprising a rotary reel, a transfer device, means for rotating the reel for coiling the article, a resilient presser device engageable with the article during winding thereof, a movable support for the presser device, means for stripping the coiled article from the reel onto the transfer device, and means for moving the movable support for the presser to keep the latter in contact with 100 the coils of the article during the stripping operation.
57. Apparatus for packaging strand-like articles comprising means for reeling such an article to form a skein, means for wrapping the skein, a transfer device provided with a plurality of holders each adapted to receive a reeled skein from the reeling means, each holder having a clamping device for holding the coils of the skein in the same relative position in which they were 110 originally reeled, and means for moving the transfer device to carry the holders successively into position to present their skeins to the wrapping means.
58. Apparatus for packaging strand-like articles comprising means for reeling such an article to form a skein, means for wrapping the skein, said wrapping means being spaced from the reeling means, a transfer device interposed between the reeling means and the wrapping means, 120 said transfer device comprising a skein holder, means for actuating the transfer device to move the holder along a predetermined path from a skein receiving position adjacent to the reel to a position adjacent to the wrapping means, means 125 for delivering a wound skein from the reeling means to said holder while the latter is in skein receiving position, means for moving the skein holder transversely of said path when positioned adjacent to the wrapping means to position the 130 skein in the field of operation of the wrapping means, and means for restoring the holder to said path after the wrapping is completed, the holder being provided with means for clamping the outer ends of the skeined article as the holder moves 135 along said path.
59. Apparatus for packaging strand-like articles comprising means for reeling such an article to form a skein, means for wrapping the skein, a skein holder, means for moving the skein 140 holder along a predetermined path from a point adjacent to the reeling means to a position adjacent to the wrapping means, a stripper associated with the reeling means and operative to deliver a reeled skein from the reeling means to said 145 150

- holder when the latter is disposed adjacent to the reeling means, and end retaining means on the holder operative to restrain both ends of the skeined article while the holder moves along its path between the reeling means and the wrapping means. 80
60. Apparatus of the class described comprising means for reeling a tipped lace, means for wrapping the reeled lace, conveyor means comprising a skein holder and means for moving the latter along a predetermined path from a position adjacent to the reeling means to a position adjacent to the wrapping means, means for delivering the reeled lace from the reeling means to the holder when the latter is disposed adjacent to the reeling means, and means on the holder operative to clamp both ends of the reeled lace in definite position while the holder is moving along said path toward the wrapping means. 85
- 10 61. Apparatus for packaging strand-like articles which comprises means for reeling the article to form a skein-like coil, means for wrapping the coil, conveyor means for transferring the coil from the reeling to the wrapping means, said conveyor means comprising elements engaging both the inner and outer end portions of the article to hold them in definite position during transfer, and means for delivering the coil from the reeling means to the conveyor means. 90
- 20 62. Apparatus for packaging strand-like articles comprising means for reeling such an article to form a skein, means for wrapping the skein, a transfer device having a skein holder, means for moving said holder into proximity to the reeling means to receive a reeled skein from the latter, and means for moving the holder into proximity to the wrapping means for disposing the reeled skein in position to be wrapped, the holder being provided with a spring actuated 100
- 25 clamping arm for positioning the outer end of the coiled article during the transfer. 105
- 30 63. Apparatus for packaging strand-like articles comprising means for reeling such an article to form a skein, means for wrapping the skein, a transfer device having a skein holder, means for moving said holder into proximity to the reeling means to receive a reeled skein from the latter, and means for moving the holder into proximity to the wrapping means for disposing the reeled skein in position to be wrapped, the holder being provided with a spring actuated 110
- 35 clamping finger adapted to apply pressure to the outermost coil of the skein to prevent disarrangement of the coils of the skein during transfer. 115
- 40 64. Apparatus for packing strand-like articles comprising means for reeling such an article to form a skein, means for wrapping the skein, a transfer device having a skein holder, means for moving said holder into proximity to the reeling means to receive a reeled skein from the latter, and means for moving the holder into proximity to the wrapping means for disposing the reeled skein in position to be wrapped, the holder being provided with a spring actuated 120
- 45 clamping finger adapted to apply pressure to the outermost coil of the skein to prevent disarrangement of the coils of the skein during transfer. 125
- 50 65. Apparatus of the class described comprising a reel, means for intermittently rotating it and for holding it stationary in delivery position, wrapping means, a transfer device having a skein holder, means for moving the skein holder into proximity to the reel and to the wrapping means respectively, means for stripping a coiled article from the reel onto each successive holder, and means for moving the holders radially outward when positioned in proximity to the wrapping means to present the coiled article to receive its wrapper. 130
- 55 66. Apparatus of the class described comprising a reel, means for intermittently rotating it and for holding it stationary in delivery position, wrapping means, a rotary transfer turret having a plurality of radial arms each provided with a radially movable coil holder having coil holding arms, and means for intermittently turning the turret alternately to position the successive holders in proximity to the reel and to the wrapping means respectively, means for stripping a coiled article from the reel onto each successive holder, and means for moving the holders radially outward when positioned in proximity to the wrapping means to present the coiled article to receive its wrapper. 135
- 60 67. Apparatus of the class described comprising a reel, means for intermittently rotating it and for holding it stationary in delivery position, wrapping means, a transfer turret having a plurality of radial arms each provided with a radially movable holder, spring means tending to retract the holders inwardly toward the center of the turret, means for turning the turret to bring said holders successively into proximity to the reel to receive a coiled article therefrom and then into proximity to the wrapping means, and cam means for moving the holders radially outward toward the wrapping means when disposed in proximity to the latter. 140

JAMES A. KERR.
